UNITED STATES PATENT OFFICE

153,015

DESIGN FOR A COMBINED WRIST WATCH
AND HOLDER STRAP THEREFOR

Oreste Pennino, New York, N. Y.

Application July 9, 1948, Serial No. 147,465

Term of patent 7 years

(Cl. D42—8)

To all whom it may concern:

Be it known that I, Oreste Pennino, a citizen of the United States of America, residing in New York, county of New York, and State of New York, have invented a new, original, and ornamental Design for a Combined Wrist Watch and Holder Strap Therefor, of which the following is a specification, reference being had to the accompanying drawing, forming part thereof.

Fig. 1 is a plan view of a combined wrist watch and holder strap therefor, showing my new design.

Fig. 2 is an edge view thereof.

The dominant features of my design reside in the portions shown in solid lines.

I claim:

The ornamental design for a combined wrist watch and holder strap therefor, substantially as shown and described.

ORESTE PENNINO.
